RAILWAY TRACK CIRCUIT

Filed April 20, 1929

FIG. 1.

FIG. 2.

INVENTOR
O. S. Field,
BY Neil H. Preston,
his ATTORNEY

UNITED STATES PATENT OFFICE

OSCAR S. FIELD, OF ROCHESTER, NEW YORK, ASSIGNOR TO GENERAL RAILWAY SIGNAL COMPANY, OF ROCHESTER, NEW YORK

RAILWAY-TRACK CIRCUIT

Application filed April 20, 1929. Serial No. 356,723.

This invention relates in general to track circuits such as used in railway practice, and has more particular reference to means for automatically maintaining the current through a track relay substantially constant regardless of change in ballast resistance.

In railway operation it is quite essential that the usual track relay connected across the entrance end, (or exit end) of each signalling block be sufficiently energized when the block is unoccupied to pick up and hold up with certainty, and at the same time that occupancy of the block will so effectively shunt the relay as to cause it to release. These considerations show that the proper operation of a track relay is a marginal affair. For example, if the normal holding current is too high, shunting may not be effective to drop the relay, whereas if normal holding current be placed so low that shunting will with greater certainty be effective, it is possible that at times the holding current may be insufficient.

Taking the above in consideration, it is seen that the usual variations in ballast resistance encountered in practice, due primarily to changes in weather conditions, may operate to cause improper operation of a track relay unless some means be provided for automatically compensating for changes in ballast resistance.

As the ballast resistance increases, the ballast leakage, or the flow of current between the rails, decreases, so that the voltage across the terminals of a track relay connected in such a circuit increases. Conversely, as the ballast resistance decreases, ballast leakage increases and the terminal voltage at the relay decreases. Unless provision be made for regulating the current flowing through the relay, this current will vary over a considerable range, and very possibly cover a range sufficient to at times prevent proper operation of the relay under occupied or unoccupied conditions of its block.

It is proposed, in accordance with this invention, to provide means in series with a track relay which automatically increases the resistance in the energizing circuit for the track relay when its terminal voltage in-

creases due to the ballast resistance increasing, and decreases resistance in the relay circuit when ballast resistance decreases. In this manner, a practically constant current flows through the track relay under unoccupied conditions of the block, regardless of changes in terminal voltage due to changes in ballast resistance.

Further objects, purposes and characteristic features of the invention will appear as the description progresses, reference being had to the accompanying drawing, showing, merely by way of example, and in no manner in a limiting sense, one form which the invention can assume. In the drawing:

Fig. 1 diagrammatically illustrates one form of the present invention.

Fig. 2 diagrammatically illustrates a second form of the present invention.

Referring to the drawing, and first to Fig. 1, a stretch of single track is shown, constituted by track rails 1 supplied with insulating joints 2 to form an insulated track section A in a usual manner, with a track battery 3 and a current limiting resistance 4 connected across the exit end of the block, (travel being in the direction of the arrow,) and a track relay TR connected across the entrance end of the block.

Imbedded in the ballast between the track rails 1 is a ground connection 5 which may be a section of rail or the like. A control battery CB has one terminal connected to this ground connection, and the other terminal connected to the winding of a control relay CR, the other end of the winding of CR being connected to one of the track rails 1. The relay CR has an armature 6 pivoted at 7, and controlling the pressure exerted on a carbon pile CP which is inserted in the energizing circuit of the track relay TR, whereby to vary the resistance of the track relay energizing circuit.

As set forth above in the introductory portion of this specification, as the ballast resistance increases, the voltage applied across the track relay at its connection to the track rails increases, and tends to increase the normal holding current through the relay, to possibly increase it so greatly as to prevent proper

shunting action upon occupancy of its block. The increase in the ballast resistance however, increases the resistance in the energizing circuit for relay CR, whereby its armature 6 decreases the pressure on the carbon pile so as to increase the resistance in the control relay energizing circuit a sufficient amount to compensate for the increased voltage across relay TR. In this manner the current is maintained substantially constant in the track relay when ballast resistance increases.

In a similar manner on decrease of ballast resistance, the voltage across the track relay decreases, but the regulating means increases pressure on the carbon pile to decrease resistance in the track relay circuit sufficiently to maintain the track relay current substantially constant.

The various instrumentalities employed in the shown embodiment of this invention, and described above, are of course only illustrative, and can be replaced by various other regulating means. Electron tubes, or other control means can be employed in this connection, and the invention contemplates such use. Also, armature 6 can be spring biased in either clockwise or counter-clockwise direction, or both, if desired. Also, ground connection 5 can be comprised of a plurality of members variously embedded in the ballast, both as regards depth and position laterally relatively to the track rails.

It should be noted that occupancy of the block does not shunt the electro-magnet or control relay CR and hence does not materially affect the automatic control, as is the case in the Howe application (Ser. No. 356,716) filed of even date herewith, and entitled "Track circuits." In this form of invention, however, occupancy does connect up the two rails by a very low resistance connection, so as to supply two multiple paths, instead of the normal single path, for flow of current from battery CB, from 5 to the left lead of relay CR, and thus affects the automatic control to a slight extent. Accordingly, unless very accurate control is required, there is no great occasion in this invention, to provide slow acting, or retarding, means in the control, as is provided in the Howe invention referred to just above.

The arrangement in Fig. 2, is the same as Fig. 1, except a double wound relay CR¹ is used, each connected at one end to 5¹, and at the other ends, connected respectively, to the two track rails 1, as shown. With this form, there is already, in normal unoccupied condition of the track section, two multiple paths from 5 through the relay CR¹. Thus, a shunting car cannot affect the automatic control to any appreciable extent.

The windings *w* and *w*¹ of relay CR¹ are connected up so that their effects due to current from battery CB¹, is cumulative, while

that due to track battery current (as 3) is opposed so as to cause no net effect.

It will be clear from the above description, that this invention provides means whereby there is assurance that after once adjusting the various track circuit constants to give proper operation under a given ballast condition, an increase in ballast resistance cannot operate to over-energize the track relay so as to prevent proper shunting upon occupancy of its block, and a decrease in ballast resistance cannot under energize the track relay so as to cause it to release when not shunted out due to occupancy of its block.

The above rather specific description of one form of the present invention has been given solely by way of illustration, and is not intended, in any manner whatsoever, in a limiting sense. Obviously, this invention can assume many different physical forms, and is susceptible of numerous modifications, and all such forms and modifications are included by this application, as come within the scope of the appended claims.

Having described my invention, I now claim:

1. In a track circuit, in combination with an insulated stretch of track, a source of electrical energy connected across one end of the track, and a track relay connected across the other end of the track, an energizing circuit for the track relay including the track rails, regulating means for automatically maintaining the normal energizing circuit through the track relay substantially constant regardless of variations in ballast resistance, said regulating means including, a variable resistance always in series with the track relay, and a control means for the resistance, responsive to changes in ballast resistance, and independent of the track circuit.

2. In a track circuit, in combination with an insulated stretch of track, a source of electrical energy connected across one end of the track, and a track relay connected across the other end of the track, an energizing circuit for the track relay including the track rails, electro-magnetic regulating means for automatically maintaining the normal energizing current through the track relay energizing circuit constant regardless of variations in ballast resistance, by increasing or decreasing the resistance to current flow through the track relay according as the ballast resistance increases or decreases, respectively, said regulating means including, a carbon pile resistance, a control relay having one terminal connected to a track rail, a ground member buried in the track ballast adjacent the track rails, and a source of electrical energy connected between another terminal of the control relay and the ground member.

3. In a track circuit, in combination with an insulated stretch of track, a source of electrical energy connected across one end of the

track, and a track relay connected across the other end of the track; regulating means for automatically maintaining the normal energizing current through the track relay substantially constant regardless of variations in ballast resistance, by increasing or decreasing the resistance to current flow through the track relay according as the ballast resistance increases or decreases, respectively, said regulating means including a double wound control relay having one terminal of each winding connected to respectively each track rail, a ground member buried in the track ballast adjacent the track rails, and a source of electrical energy connected between the ground member and a terminal common to the two windings of the control relay.

4. In a track circuit, in combination with an insulated stretch of track, a source of electrical energy connected across one end of the track, and a track relay connected across the other end of the track; regulating means for automatically maintaining the normal energizing current through the track relay substantially constant regardless of variations in ballast resistance, by increasing or decreasing the resistance to current flow through the track relay according as the ballast resistance increases or decreases, respectively, said regulating means including a double wound control relay having one terminal of each winding connected to respectively each track rail, a ground member buried in the track ballast adjacent the track rails, and a source of electrical energy connected between the ground member and a terminal common to the two windings of the control relay, the two windings of the control relay being connected to said source of electrical energy so that their energized effect due to said source of electrical energy, is cumulative.

5. In a track circuit, in combination with an insulated stretch of track, a source of electrical energy connected across one end of the track, and a track relay connected across the other end of the track; regulating means for automatically maintaining the normal energizing current through the track relay substantially constant regardless of variations in ballast resistance, by increasing or decreasing the resistance to current flow through the track relay according as the ballast resistance increases or decreases, respectively, said regulating means including a double wound control relay having one terminal of each winding connected to respectively each track rail, a ground member buried in the track ballast adjacent the track rails, and a source of electrical energy connected between the ground member and a terminal common to the two windings of the control relay, the two windings of the control relay being connected to said source of electrical energy so that their energized effect due to said source of electrical energy, is cumulative, and the energized

effect of the said two windings, due to the track battery, is opposing.

6. In a track circuit, in combination with an insulated stretch of track, a source of electrical energy connected across one end of the track, and a track relay connected across the other end of the track; regulating means for automatically maintaining the normal energizing current through the track relay substantially constant regardless of variations in ballast resistance, by varying the resistance to current flow through the track relay according as the ballast resistance varies, said regulating means including a double wound control relay having one terminal of each winding connected respectively to each track rail and a source of electrical energy connected between the ground and a terminal common to the two windings of the control relay.

In testimony whereof I affix my signature.
OSCAR S. FIELD.
